PICTURE PUZZLE TOY

Emmanuel Dobrowsky, New York, N. Y.

Application December 13, 1946, Serial No. 716,120

4 Claims. (Cl. 273—155)

1

This invention relates to a toy and more particularly to a picture puzzle toy having a mechanism which enables the user to make up a whole picture from its separate parts.

In the construction of certain picture puzzle devices prior to this invention wherein a composite picture is reproduced by matching the various parts at will, the mechanism employed in operating the movement of the picture segments necessitated the use of complicated rollers, knobs and picture ribbons wrapped around said rollers. In addition, certain devices as related above employed telescoped shafts with the control knobs arranged in line with an axis common to all. The latter arrangement limited the number of segments used in the composite picture puzzle due to the fact that each additional segment required a separate control knob and another telescoped tube which would make the control mechanism bulky, unwieldy and wholly too complicated for a child to operate.

It is therefore the main object of this invention to provide a picture puzzle toy having a control mechanism which is simple for a child to operate in the adjustment of the picture segments to make the composite picture.

Another object of this invention is to provide a picture puzzle toy which will provide for an unlimited combination of picture segments and composite pictures requiring a minimum of effort and materials in assembling the same.

Other objects and advantages will appear from the following description considered in connection with the accompanying drawings, in which:

Fig. 1 is a front elevational view of the picture puzzle device; Fig. 2 is a cross-sectional view of Fig. 1, taken along the line 2—2; Fig. 3 is a top plan view of the device; Fig. 4 is a cross-sectional view of Fig. 1 taken along the line 4—4; Fig. 5 is a side view, partially in X-ray, showing the relationship between the closed cover and the internal parts of the device; Fig. 6 is the same view as Fig. 5 with the cover in the open position; Fig. 7 is a front elevational view of another embodiment with the control wheels in a frontal position above the observation window; Fig. 8 is a cross-sectional view along the lines 8—8 of Fig. 7 showing the position of the cover in the closed and open positions.

Referring now to the drawings and in particular to the picture puzzle toy shown in Figs. 1, 2, 3 and 4, the toy comprises a frame 1 in which the moving parts of the toy are mounted. This frame 1 has an observation window 2 made, for example, of clear plastic, situated in the front

2

wall 3 while the rear wall comprises a lid 4 which is a rigid part of the bottom wall 5 connected by a hinge 6 to the front wall 3. A pair of clips 7 are attached by a plurality of washers 8 and screws 8A to the rear part of the side walls 9 so that when said lid 4 is in the closed position, the clips 7 clamp the lid 4 and hold it in the closed position. Said clips 7 are rotatable around said washers 8 and screw 8A. A plurality of openings 10 separated by partitions 11 are cut in the angular part 12 situated in the upper portion of said lid 4. In each opening 10, a wheel 13 made, for example, of rubber, is located and supported by an axle 14 that may be in the form of a single rod extending through the center of each wheel 13 so that all the wheels 13 lie in a parallel position within the plurality of openings 10.

Another axle 15 supports a plurality of picture wheels 16 within said frame 1. Said wheels 16 may have spokes 17 and may, for example, be made of plywood, cardboard or other suitable material. Slots 18 are cut on the inside of the side walls 9 to the center of the frame 1. The bottom 19 of the slot 18 is constructed to hold and support said axle 15. A piece of resilient material 20 which may be, for example, rubber, felt or other suitable material is located at the bottom 19 of said slot 18, so that when said lid 4 is in the closed position, the small wheels 13 compressed against the respective peripheries of said picture wheels 16 and said resilient material 20 aid in maintaining the pressure between said wheels 13 and 16 which rotate around their respective axles 14 and 15. Washers 21 separate the end picture wheels 16 from the side walls 9 while thin washers 22 separate said plurality of picture wheels 16 from each other.

Segments of pictures 23 are pasted on the outer surfaces of said picture wheels 16.

Figs. 5 and 6 show the picture puzzle toy with said lid 4 in the closed and open positions respectively.

Referring now to Figs. 7 and 8, the toy discloses another embodiment with the observation window 2 located in the lid 4 which pivots on a hinge 6. As shown, particularly in Fig. 7, the plurality of wheels 13 are set in openings 10 located just above said observation window 2 in said lid 4. Rotating clips 24 are held to the front of the frame 1 by means of washers 8 and screws 8A. Said lid 4 has a cut-out end 25 which fits a mating groove 26 located in the front of said frame 1 just behind said clips 24, so that said clips 24 may be rotated over said

cut-out end 25 of said lid 4 when it is in the closed position.

The device operates as follows:

When a child wishes to make a composite picture out of the various segments 23, he looks through the observation window 2 and rotates the wheels 13 in either direction until he obtains a combination of segments 23 sufficient to produce a composite picture. When wheel 13 is rotated, it causes the picture wheel 16 to rotate due to the friction pressure between the surfaces of wheels 13 and 16. This friction pressure is maintained by means of the rubber or felt cushion 20 set in the bottom 19 of the slot 18 which supports the axle 15 of the picture wheel 16. In order to increase the friction surface of wheels 13, horizontal ridges or other suitable design, for example, may be molded on the external surface of said wheels 13. When the operator of the toy wishes to change the pictures on the surface of wheels 16, said wheels 16 may be removed from the frame 1 by lifting the lid 4 and drawing the entire assembly consisting of picture wheels 16 and axle 15 along the slots 18 until said picture wheels 16 are clear of the frame 1. When the wheels 16 are replaced, they are inserted in the frame so that the axle 15 slides into the slot 18 until it reaches the felt pad 20 located at the bottom 19 of said slot 18. Then the lid 4 is closed, which brings the wheels 13 in pressure contact with picture wheels 16. Clips 7 shown in Fig. 3 are then snapped into place to hold the lid 4 closed against the pressure of said felt pad 20.

In the other embodiment shown in Figs. 7 and 8, said lid 4 is closed and pressure is maintained by rotating said clips 24 over the surfaces of the cut-out ends 25 of the lid 4.

As will be seen from the above description, the invention discloses a picture puzzle toy which presents a novel and simple device for producing a composite picture from a certain number of segments of said picture.

It eliminates telescoping tubing and control knobs by providing simple friction wheels that directly control the movement of the picture segments on the peripheries of a plurality of picture wheels.

In addition, the picture puzzle may have a few segments or many segments depending on the age of the child. The number of picture segments which may be used is unlimited and may be varied in complication sufficient to challenge the ingenuity of children of all ages.

While, in disclosing the principles of my invention and its preferred embodiment, I have described various detailed structure and relationship, it will be understood that such embodiment and details are given by way of example only and not as limiting the scope of my invention.

I claim:

1. A picture puzzle toy comprising a frame hav-

ing a hinged lid capable of being opened and closed, an observation window located in said lid in the closed position, a plurality of picture wheels situated within said frame, means for rotatably mounting said picture wheels within said frame, picture segments affixed to the peripheries of said picture wheels, a plurality of activating members comprising wheels mounted for individual and separate rotation on said lid so that they bear against the picture wheels when the lid is closed and located on said lid close to said observation window and means for separating said activating members from each other.

2. A picture puzzle toy as claimed in claim 1, in which said lid has a notched end, said frame having a front wall and a notch in said front wall corresponding to that in the lid so that when the lid is closed the outer surface of the lid and the front wall will lie flush and a locking means attached to the front wall and adapted to rotate over the notched end of the lid when said lid is in the closed position.

3. A picture puzzle toy as set forth in claim 1, in which a plurality of parallel apertures are arranged in the lid, the activating members adapted to fit within said apertures with a portion of the activating members projecting out of said apertures and beyond the surface of said lid and said activating members mounted on the lid so that their axis of rotation is at a distance slightly less than the radii of the wheels of the activating members from the peripheries of the picture wheels when the lid is in the closed position, whereby the wheels of the activating members will be compressed against said picture wheels when the lid is in the closed position.

4. A picture puzzle toy as set forth in claim 1 in which the mounting means for the picture wheels comprises a slot located along the inside wall of said frame, having one open end and an axle supported in the bottom of said slot whereby the picture wheels may be removed from the frame by moving the axle to the open end of the slot.

EMMANUEL DOBROWSKY.
